UNITED STATES PATENT OFFICE.

ERWIN A. GEIGER, OF RIDGEWOOD, NEW JERSEY, AND HENRY T. JENNINGS, OF BROOKLYN, NEW YORK, ASSIGNORS TO RAPID ADDRESSING MACHINE COMPANY, A CORPORATION OF NEW YORK.

CARD DAMPENING AND STENCILING MACHINE.

Application filed March 25, 1924. Serial No. 701,617.

To all whom it may concern:

Be it known that we, ERWIN A. GEIGER and HENRY T. JENNINGS, citizens of the United States of America, residing at 5 Ridgewood, Bergen County, State of New Jersey, and Brooklyn, city of New York, county of Kings, and State of New York, respectively, have invented certain new and useful Improvements in Card Dampening and Stenciling Machines, of which the following is a specification.

Our invention relates to apparatus for dampening and stenciling cards having panels of long, loosely felted fibre paper 15 treated with a coating which can be removed by the blow of the type of an ordinary typewriting machine and is designed to assemble in one apparatus the necessary devices for feeding such cards successively from a suitable magazine through a dampening device 20 and then to the typing machine which is arranged to operate on them while still in the card guides of the apparatus.

Heretofore it has been customary for the 25 typist to pick up such cards one by one, dampen them with a moist brush and then adjust the same in the typewriting machine preparatory to stenciling the desired name and address therein. With our invention 30 all these operations are automatically performed by merely pressing down a pedal placed under the machine.

The best form of apparatus at present known to us embodying our invention is 35 illustrated in the accompanying three sheets of drawings in which—

Fig. 1 is a front elevation of the machine the typing machine being indicated in broken lines.

Fig. 2 is a side elevation.

Fig. 3 is a plan view with the card magazine shown in section on line 3—3 of Fig. 2, parts of the table broken away and portions of the exposed structure shown in section.

Fig. 4 is a vertical longitudinal section of portions of the table and connected parts with others broken away.

Fig. 5 is a similar view of parts of the apparatus shown in Fig. 4 drawn on a larger scale, the card dampening apparatus being in position for receipt of a card.

Fig. 6 is a vertical cross section on line

6—6 of Fig. 4, taken on an enlarged scale and parts broken away, and

Fig. 7 is a diagram showing the various stations of the progress of a card from magazine to receiving hopper.

Throughout the drawings like reference characters indicate like parts.

1 is the main supporting frame on which rests the table 2, carrying at one end the card magazine 3 in which is shown a stack of cards 54. The bottom card of this stack rests in the card guides 4, which extend out horizontally through the middle portion of table 2 and terminate over the receiving hopper 5. 6 represents generally a dampening apparatus located in operative relation to the cards passing along said guide 65 between the magazine and the hopper. 7 is a typewriting machine of the class known as check-writing or billing machines, adapted to operate upon a card held in the guides after it has passed the dampener. 8 is a feed claw pivoted at 9 on the carriage 10, which slides on the guides 11 so disposed that said claw may grasp the card at the bottom of the stack and force the same out into the position marked "First station" in 70 Fig. 7. This feed device is reciprocated by the link 12, pivoted to it at one end and at the other end to the upper arm of bell crank 13 pivoted at 14 in the housing 15, extending downward from the table 2. The other arm of bell crank 13 is connected by adjustable 75 pivot link 16 to pedal lever 17 pivoted at 18 in the housing 19 supported by the cross bar 20 in the lower portion of frame 1, as clearly shown in Figs. 1 and 2.

While various forms of dampening apparatus might be employed, we have illustrated in detail in Figs. 3, 4 and 5, the preferred form of such apparatus certain elements of which are adapted to cooperate 95 with the typing machine. This apparatus comprises a pair of levers 21, slotted at 23 to cooperate with another pair of levers 22, carrying pins 24 engaging said slots 23, which levers are carried by shafts 25 and 26 respectively supported by pivot pins 35, 36 (best shown in Fig. 3) set in housings 45 and 46 which project downwardly from table 2. The vertically movable platen 29 in said table is supported on toes 27, 28, 100 formed on shafts 25, 26, respectively, and

engaging the bearing lugs 30, 31, projecting downwardly from the platen 29. The platen 29 is guided by screws 37, set in the under side of table 2, and extending through 5 perforated lugs 38 projecting from the corners of platen 29. Normally the levers 21 and 22 are held up in the position shown in Fig. 4 by means of the strong tension springs 34 connecting arms 32 on shaft 26 10 with arms 33 on shaft 25. This brings the platen 29 up into the plane of the table 2, as shown in Fig. 4. To depress said platen and expand spring 34, a downward tension may be applied to levers 21 by means of the 15 chain 55, the upper end of which is fastened to the cross bar 56 connecting the ends of the two levers 21, while the lower end of said chain is connected to the forward portion of the pedal lever 17. As shown in Fig. 20 3, there are duplicate sets of the levers 21, 22 and springs 34, and cooperating parts, one set on each side of platen 29.

39 is a bar or strip set in an opening in platen 29 and extending across said platen 25 to serve as a support for a ribbon of felt or other absorbent material 40, the downwardly hanging ends of which are immersed in a suitable dampening fluid in the reservoir 41. By capillary action, the portion of the 30 ribbon 40 stretching across the bar 39 is maintained in a moist condition and so forms a moist section of the surface of the platen 29. 42 is a card pressing strip of approximately the same outline as the bar 35 39 and supported above the same by ears projecting downward below the under side of the table 2, and fastened by pins 42 to the long arms of levers 43. The other, shorter arms of levers 43 are connected by shaft 40 50, which extends through housings 47, projecting downwardly on the under side of the platen 29. 52 is a facing of compressible and preferably absorbent material such as 45 felt on the under side of the compressor strip 42. These levers 43 are pivoted on pins 44 set in housings 51.

As the result of the above construction it is obvious that when the pedal 17 is pressed down and the parts pulled into the position 50 shown in Fig. 5 against the tension of springs 34, the depression of the platen 29 will raise the long arms of levers 43 and with it the presser strip 42 into the position there shown in Fig. 5.

55 When the pedal 17 is released by the operator springs 34 throw the parts into the position shown in Fig. 4 with the presser strip 42 forced down on the upper surface of the card which is in the second station 60 shown in Fig. 7, within the grasp of the moistening device. At the same time, of course, the moistening ribbon 40 is forced up against the under surface of said card and during this operation the feed claw 8 is traveling back to the full line position shown in

Fig. 4 ready to grasp another card at the next operation.

48 is a panel of celluloid or other suitable elastic material so placed as to come under the card when it is in the third station 70 shown in Fig. 7, after it has been dampened and advanced to the operating zone of the typing machine 7.

49, 49, represent friction stops, shown in Fig. 5, adapted to bear on the cards in stations 1 and 3, and prevent them being carried by their inertia beyond their proper stations and so interfere with the proper operation of the dampening and typing devices. 75

The typing machine 7 is mounted on rollers 53, shown in Figs. 1 and 2, so that it may be moved horizontally to properly adjust it with reference to the card in station 3 beneath it, or to remove it entirely from over 80 the platen 29 and card guides so that access may be had to them. 85

The operation of the above described apparatus is as outlined in the foregoing description, it being understood that when the operator is pressing down on pedal 17 and thereby causing the feed claw 8 to advance from the full line position shown in Fig. 4 to that shown in broken lines therein, the platen 29 is lowered slightly and the presser strip 42 raised, as shown in Fig. 5 so that the entire line of cards in the guides 4 are free to move forward under the urge of said feed claw, and that when the operator removes his foot from pedal 17 and springs 34 90 retract the claw 8 and the line of cards are 95 at rest, the platen 29 rises and, cooperating with the presser strip 42, clamps one card in the dampening device while the card ahead of that is lifted into a position such that it 100 may be stencilized by the typing machine 7. 105

One type bar 58 of the typing machine is shown depressed to operate on a card in Fig. 2.

Among the advantages of our invention 110 may be mentioned the accuracy with which the cards are made to register with the dampening and typing devices in the course of the progress of the cards along the card guides, the efficient action of the dampening device, due to the progressive application of the pressure of the dampening members 40 and 42, which make initial contact with each card at the forward edge thereof and then 115 extend their areas of such contact across the card to the rear edge thereof, as the result of the presser strip 42 swinging from pivots located below the level of the ribbon supporting bar 39, and to one side thereof, and the even application of moisture resulting 120 from the card being thus clamped between upper and lower moisture absorbing surfaces. The carrying of the liquid reservoir on an immovable support avoids any tendency 125 to slop the liquid, and the transmission 130

of the liquid to the moistening surfaces by capillary action through a loosely hanging ribbon ensures an even and certain moistening of the card. The herein described preferred construction also is compact, light in weight and reduces internal friction to a minimum, while the operating of the entire mechanism from one set of springs 34, 34, flexed by one pedal, eliminates backlash and 10 lost motion.

Having described our invention we claim:

1. In a card stenciling apparatus the combination of horizontal card guides, a magazine for cards located at one end of said guides, a typing machine located over said guides near the other end thereof adapted to operate on a card in said guides and adjustable in a horizontal plane, a dampening device located along said guides between 15 said magazine and said typing machine, and means for feeding cards along said guides from magazine to typing machine.
2. An apparatus such as set forth in claim 1 combined with friction stops for holding 25 the card at intervals in its progress through said guides one stop being located adjacent the dampening device and another adjacent the typing machine.
3. In a card stenciling apparatus the combination, with guides for the cards, of a dampening device comprising a reservoir of 30 fluid below said guides, a platen normally located slightly below the plane of said guides and having a support for a ribbon of absorbent material supported thereby and extending down into said reservoir, and means for pressing each card against said ribbon as said card is passed along said guides.
4. A combination such as set out in claim 40 3 in which the card pressing device comprises a swinging member having a presser face located above the card but supported on a pivot below the platen, whereby said presser face on its downward movement makes contact initially with one edge of the 45 card and then progressively extends its area of contact across the card face to the opposite edge thereof.
5. A combination such as set out in claim 50 3 in which the card pressing device comprises a swinging member having a presser face composed of yielding absorbent material located above the card but supported on a pivot below the platen, whereby said presser face on its downward movement makes contact initially with one edge of the 55 card and then progressively extends its area of contact across the card face to the opposite edge thereof.
6. A combination such as set out in claim 60 3 in which the said pressing device comprises means for raising the ribbon support and forcing said ribbon against the under surface of the card.
7. In a card dampening device the combination, with guides for the cards and intermittently acting means for feeding the cards along said guides, of a vertically movable platen having a dampened portion of its face located slightly below the level of the 65 card in the guides when said feeding means is acting on the card, a presser member located over said dampened portion and slightly above the card level during the same period, and means for raising said platen and 70 lowering the presser member while said feeding means is not acting on the card.
8. In a card dampening device the combination, with guides for the cards, of a reciprocating claw for feeding a series of cards 75 along said guides, a dampening device located adjacent the guides, a vibrating pedal, and connections from said pedal to said claw and said dampening device, whereby when said pedal is pressed downward the claw is moved toward the dampening device, and when said pedal is moved upward said claw is moved away from said dampening device and the latter is caused to operate on a card 80 at rest in operative relation thereto.
9. In a card dampening device the combination, with a supporting frame, card guides thereon and means for feeding a series of cards along said guides, of a vertically movable platen below said guides having a portion of its surface dampened, a presser member above said guides overhanging said dampened portion of said platen and supported on a lever pivoted on the main frame 85 and having its other end connected to said platen, and means for raising and lowering said platen; whereby, when the platen is raised, the presser member is lowered to force any card in the guides below it against the dampened portion of the platen, but 90 when said platen is lowered said presser member is raised and the cards are left free to be moved along the guides.
10. A combination such as set out in claim 9 in which the platen moving means 100 comprises two parallel shafts provided with toes engaging the under surface of said platen, levers on said shafts united by pin and slot connections, a spring normally tending to so rotate said shafts as to raise said toes, and a pedal connected to one of said levers and adapted to rotate said shafts in reverse directions.
11. In a card stencilling apparatus the combination, with a set of card guides and intermittently operating means for feeding a series of cards along the same, of a typing machine located over said guides and adapted to force type down on any card located in the guides beneath it, a vertically movable platen below the guides and extending under said typing machines, and means for lowering said platen when said card feeding means is acting on the cards; whereby cards 110 may be driven over the lowered platen into 115
12. A combination such as set out in claim 11 in which the platen moving means 120 comprises two parallel shafts provided with toes engaging the under surface of said platen, levers on said shafts united by pin and slot connections, a spring normally tending to so rotate said shafts as to raise said toes, and a pedal connected to one of said levers and adapted to rotate said shafts in reverse directions.
13. In a card dampening device the combination, with guides for the cards and intermittently acting means for feeding the cards along said guides, of a vertically movable platen having a dampened portion of its face located slightly below the level of the card in the guides when said feeding means is acting on the card, a presser member located over said dampened portion and slightly above the card level during the same period, and means for raising said platen and 130 lowering the presser member while said feeding means is not acting on the card.

position under the typing machine, but the platen is raised into operative relation with the typing machine while the cards are at rest in said guides.

- 5 12. A combination such as set forth in claim 11, in which the portion of the platen under the typing machine is provided with a resilient surface adapted to cooperate therewith.
- 10 13. In a card dampening machine the combination of reciprocating dampening members, a cooperating reciprocating card feeding device, mechanism connecting the two, spring means tending to operate said train of connected mechanisms by its flex-
- 15

ure in one direction, and a lever adapted to be reciprocated by the operator to flex said spring and move said mechanisms in the opposite direction.

14. In a card dampening machine the combination of a supporting frame, a reservoir for dampening liquid rigid on said frame, dampening members movably mounted on said frame, and a ribbon of absorbent material held by said dampening members and having a free end suspended loosely in said reservoir.

ERWIN A. GEIGER.
HENRY T. JENNINGS.
